Attorney

UNITED STATES PATENT OFFICE.

JULIUS SCHMID, OF MONTGOMERY, NEW YORK.

POWDER PUFF.

Application filed October 12, 1921. Serial No. 507,324.

To all whom it may concern:

Be it known that I, JULIUS SCHMID, a citizen of the United States, residing at Montgomery, in the county of Orange and State of New York, have invented new and useful Improvements in Powder Puffs, of which the following is a full, clear, and exact specification.

My invention relates to powder puffs and refers particularly to powder puffs which, during the application of powder carried thereby, will present a smooth and soft surface to the skin.

It also possesses other valuable characteristics which are evident upon a consideration of this specification and the accompanying drawings.

Powder puffs, composed of some material capable of carrying fine powders have been found to be a convenient means for applying toilet powders to the face and other portions of the body, and have been largely adopted for this purpose.

Powder puffs suitable for the above described purposes must not only be capable of carrying the desired powder but they must also be of an extremely soft and pliable nature, free from all coarse and hard elements, in order that they will not scratch, or injure, the most delicate of skins.

In addition to the above requirements, they should be of such form and construction that the entire powder-carrying surface may be applied to the skin in order that the powder may be applied evenly and uniformly and should be of such a character that they may be protected hygienically while being carried.

The powder puff of my invention possesses all of the above and other valuable features.

The present known powder puffs comprise a soft powder-carrying surface attached to a back, or supporting member, by means of stitching around the edges thereof, practically the entire upper face thereof being covered by the powder-carrying means.

It is evident, therefore, that in using a powder puff of the described construction, the thumb of the user must cover at least a portion of the powder-carrying surface, thus reducing the efficiency of the puff, as it reduces the surface capable of being applied to the skin, causes folds in the face of the puff and is liable to bring the thumb in contact with the skin, all of which are objectionable features.

It is to be further noted that, in the employment of puffs of the described character, the harsh stitching around the edge thereof will be brought into contact with, and drawn over, the skin, causing the liability of scratches and abrasions in addition to the unpleasantness of such contact.

A further objection to powder puffs of this character is that the powder-carrying surface is exposed when not in use, and hence, becomes soiled with the resulting danger, when applied to the skin.

I have discovered that a powder puff, free from these objections, can be made by attaching the powder-carrying member to a supporting member, or back, extending beyond the powder-carrying member in such a manner that the attaching means, as stitching, can not possibly come into contact with the skin, and by attaching two such powder-carrying members to one supporting member in such a manner that they can be folded to abut upon each other, when not in use, thus protecting them from being soiled, or injured.

In the particular form of the device of my invention, shown in the accompanying drawings, similar parts are designated by similar numerals.

Figure 1 is a top view of one form of the device of my invention in open position, partly broken away.

Figure 2 is a section through the line 2—2 of Figure 1.

Figure 3 is a top view of Figure 1, in folded position.

Figure 4 is a section through the line 4—4 of Figure 3.

The particular form of the device of my invention, as shown in the accompanying drawings, comprises two powder-carrying members composed of lamb pelts, that is, the skins 10, 10' with its naturally attached wool 11, 11'. The powder-carrying members are attached by means of stitching 12, 12' to a supporting member having the form of two tangential annular members 13, 13', the stitchings being so positioned as to be outwardly protected by the wool 11, 11'. When the device is folded, as shown in Figures 3 and 4, the wools 11, 11' will abut upon each other and the device may be retained in folded position by the clasp, or fastener, 14, 14'.

It is evident, upon a consideration of the drawings and the explanation thereof, that

my invention presents a device which may be firmly grasped by the extended portion of the supporting member, thus allowing the employment of the full face of the powder-carrying member and preventing the fingers of the user from practical contact with the powder-carrying member and powder carried thereby, and, at the same time, prevents the skin, upon which the device is used, from 10 coming into contact with the hard stitching incident to devices of this character.

A further advantage of my device, as illustrated and described, is that, when not in use, it can be so folded as to protect the 15 two powder-carrying members.

My invention, therefore, presents a new and novel device of the character described having valuable and useful properties not found in previously known powder puffs.

20 I do limit my self to the particular size, shape, or material employed in the device of my invention, as shown and described, all of which may be varied without going beyond the scope of my invention as shown, described and claimed.

What I claim is:—

1. In a powder puff, in combination, a non-porous, soft, pliable carrying member;

two powder-carrying members attached to one face of the carrying member so positioned that the edges thereof will not abut upon each other when the device is in open position, the supporting member extending beyond the powder-carrying members, and means for fastening the powder-carrying members in face abutment position when the device is folded. 30 35

2. In a powder puff, in combination, a non-porous, soft, pliable carrying member; two powder-carrying members stitched to one 40 face of the carrying member so positioned that the edges thereof will not abut upon each other when the device is in open position, the supporting member extending beyond the powder-carrying members and the 45 stitching being so situated as to be maintained from contact with a surface to which the powder-carrying members are applied, and means for fastening the powder carrying members in face abutment position when 50 the device is folded.

Signed at New York, in the county of New York and State of New York this 6 day of October, 1921.

JULIUS SCHMID.
